(57) **CLAIM**

I claim the ornamental design for a point of sale display box, as shown and described.

DESCRIPTION

FIG. 1 is a front perspective view of a point of sale display box;

FIG. 2 is a rear perspective view of the point of sale display box;

FIG. 3 is a right side elevation view of the point of sale display box;

FIG. 4 is a left side elevation view of the point of sale display box;

FIG. 5 is a front elevation view of the point of sale display box;

FIG. 6 is a rear elevation view of the point of sale display box;

FIG. 7 is a top plan view of the point of sale display box; and,

FIG. 8 is a bottom plan view of the point of sale display box. The broken lines depict portions of the article that form no part of the claimed design.

1 Claim, 3 Drawing Sheets
